UNITED STATES PATENT OFFICE

CHARLES W. GREEN, OF ILION, NEW YORK, ASSIGNOR TO REMINGTON ARMS COMPANY, INC., A CORPORATION OF DELAWARE

CASH REGISTER

Application filed December 18, 1922. Serial No. 607,609.

This invention relates to improvements in cash registers and the totalizers used therein and particularly to the transfer or carrying mechanism.

5 A broad object of the present invention is to provide a suitable mechanism for positively transmitting motion from each adding wheel of a lower order to the adding wheel of next higher order when the lower order 10 adding wheel has completed a full rotation.

More specifically it is an object of the present invention to provide a transfer mechanism comprising a trip pawl actuated by a trip device associated with the wheel of the 15 lower order to set a transfer pawl in its transfer position in order that the latter may be actuated during a regular operation of the machine to advance the wheel of the next higher order one step.

20 Further objects of the present invention are to prevent accidental displacement of the totalizer wheels when out of engagement with their actuating segments and to preclude the possibility of over-carrying of the totalizer wheel when the machine is subjected to 25 improper usage.

With these and incidental objects in view the invention consists in certain novel features of construction and combination of 30 parts, the essential elements of which are set forth in appended claims, and a preferred form of embodiment of which is hereafter described with reference to the drawings which accompany and form part of the specification.

35 Of said drawings:—

Fig. 1 is a transverse sectional view of the machine to which this invention is applied and shows the means for actuating the totalizers and the transfer operating arms for 40 effecting transfers.

Fig. 2 is a view in side elevation of one of the totalizers with parts broken away.

Fig. 3 is a view taken on the line 3—3 45 of Fig. 2 showing the totalizer in its normal position.

Fig. 4 is a view of the transfer mechanism showing how transfer by transfers are effected.

50 Figs. 5, 6 and 7 are views the same as Fig.

3 but with the operating parts in different positions.

Fig. 8 shows views in perspective of the various parts of the transfer mechanism.

Fig. 9 illustrates a part of a transfer operating arm and associated complementary cams.

Fig. 10 is a section through the machine showing a suitable form of totalizer engaging mechanism.

Fig. 11 is a plan view of the transfer actuating mechanism, showing the relative positions of the cams for actuating the transfer pawls of the various denominational orders, and also showing the location of the 65 totalizer actuating racks with respect to the transfer arms.

Fig. 12 is a sectional view taken on the line 12—12 of Fig. 11 showing the spiral arrangement of certain of the cam portions 70 on the cam members.

Fig. 13 is an elevational view taken on the line 13—13 of Fig. 11 showing the contour of one of the cams for the highest denominational order.

Fig. 14 is a collective view showing a pair of complementary cams for the lowest denominational order.

In the accompanying drawings the improvements are shown in connection with a 80 machine of the general type fully shown in the pending applications for United States Letters Patent S. N. 263,125, filed November 19, 1918, and S. N. 283,720, filed Mar. 20, 1919, by Frederick L. Fuller as well as 85 in the British Patents 135,465, 140,363, 157,823, 157,824 and 157,825, of July 11, 1921. Only such parts of the machine as are directly involved in the present invention are 90 described herein, however, and reference should be made to the applications mentioned for any information desired as to the construction and operation of the remaining parts of the machine.

Although the improvements have been 95 shown applied to the machines shown and described in the above cited applications, it is to be understood that the improvements are capable of being applied to or embodied in accounting machines generally without 100

departing from the spirit of the invention.

Described in general terms the illustrative machine comprises a series of manipulative devices such as keys 20 operable to actuate totalizing mechanism and mechanism for entering the items on a record strip.

The keys 20 are pivoted upon a rod 21 and resting upon the rear ends of the keys is a key coupler 22 pivoted at 23. When the outer ends of the keys are depressed the coupler is rocked clockwise about its pivot and its nose 24 enters the notches 25 in the rear ends of the keys. The construction and purpose of key coupler mechanism are well known in the art and need not be discussed herein.

As shown in Fig. 1, each key 20 is formed with an upwardly extending arm 26 carrying a stud 27 engaging a slot 28 in a plate 29 rigidly mounted in a frame 30 loosely mounted on the shaft 31. The slots 28 in plates 29 are graduated so that each of the keys will impart a different degree of movement to the frame 30. The plates are furthermore provided with arcuate slots 36 to permit the upward tilting of the cam plates without interfering with the rollers on the remaining unoperated keys. Secured to the frame 30 is a segmental rack 301. It is to be understood that the keys 20 are arranged in banks and that for each bank there is a differentially actuated frame 30 and its corresponding segment rack. Each segment is always in mesh with a pinion rigid with its corresponding item type wheel 32 and sets up a number which corresponds to the value of the key depressed.

Mounted below the item type carriers 32 and operable by the segmental racks hereinbefore mentioned are two totalizers 33 and 34, designated as totalizers "A" and "B" in Fig. 1 of the drawings. These may be utilized for the purpose of registering amounts for separate departments or clerks or in any other manner where it is desired to segregate the transactions into two classes and they have manipulative means associated therewith in order that either totalizer may be operated to register amounts of the various transactions.

Connected to the key coupler is a double rack 341, the connection being such that as the coupler is rocked by the keys the rack is raised or lowered, and drives a shaft 35 in such a manner that a complete reciprocation of the coupler will effect a complete rotation of the shaft. The shaft 35 carries cams and other devices for operating various parts of the mechanism. The mechanism for effecting rotation of the shaft has not been shown or described in detail because it is so old and well known in the art.

In the Fuller application No. 283,720 there are shown two special keys which are designated as "Clerks" or "Coupler lifting keys" indicated by reference numeral 101 in

Figure 10. These keys have certain functions, one of which is to serve as a means whereby the key coupler 22 may be partially raised to what may be termed the coupling position, in which position other keys representing the nature and amount of the transaction may be engaged with the coupler so that a complete operation of all the keys so engaged with the coupler may be effected further by pressure applied to any engaged key. For further information relative to this construction reference may be had to the Fuller application just mentioned.

As shown more fully in the U. S. application S. N. 263,125 and in the British patents previously mentioned the totalizers A and B are pivotally mounted between side frames so that their pinions are capable of being rocked into engagement with their respective actuators. The engagement of the totalizer A with its actuator is under control of its corresponding Clerk's or Coupler lifting key A while the totalizer B is placed in operation by means under control of its associated Clerk's or Coupler lifting key B. The engagement of the totalizer pinions with their associated actuators is effected during the time that the Clerk's or Coupler lifting key is depressed to its coupling position. Other keys may now be engaged with the coupler and upon further depressing one or more of such other keys the pinions will be actuated an amount commensurate with the value of the key depressed. At the extreme end of the downward stroke, or, if desired, during the first part of the upward stroke of the keys, the selected totalizer is disengaged from the actuators and remains disengaged during the time the keys are returned to their normal position. This mechanism will be briefly explained herein in order that the present invention may be more fully understood. However, for a more detailed description and showing reference may be had to the British patents or application S. N. 263,125 which disclose one suitable form of this mechanism.

Referring particularly to Figure 10 of the drawings, there is pivotally mounted upon a transverse rod 84 a lever 85 carrying rollers co-operating with a pair of complementary cams 86 attached to the driving shaft 35. The lever 85 is riveted to a bail member 87 having an integral forwardly extending arm 88 carrying a pin 89. The profile of the complementary cams is such that the bail 87 and the lever 88 are given an oscillating movement during each operation of the machine and this movement, as will be explained, will effect the engagement of the pinions 45 of a selected totalizer with the actuating racks 301.

Adjacent the frames of the totalizers A and B are two totalizer controlling slides 90, 91 which are guided at their upper ends by means of the shaft which supports the item

printing wheels 32 and are slotted at their lower ends so as to engage the stud 89 carried by the lever 88. Each of the slides is formed at its upper end with a cam slot 92 engaging the shaft 43 of its associated totalizer. Due to the above construction it will be evident that when either slide 90 or 91 is reciprocated the cam slot 92 of that plate co-operating with the totalizer wheel supporting shaft 43 will rock the associated totalizer frame about its pivot to bring its pinions into and out of engagement with the actuating racks.

Loosely mounted upon the pin 89 are two totalizer throwout plates 93 and 94 of identical form, the one associated with the slide 90 for upper or "A" totalizer being indicated by reference character 93 and the one associated with slide 91 for the "B" or lower totalizer by reference character 94. Each cam plate 93, 94 is provided with a cam slot 95 co-operating with a stud 96 on the associated control slide, so that by means of the connections just described the oscillatory movement given to the lever 88 will be imparted to the control slides 90, 91.

Loosely mounted upon a shaft 97 are a plurality of throw-out bails 98, each having integral therewith a downwardly extending arm 99 bifurcated to receive a pin 100 carried by its associated totalizer throw-out plate 93, 94. The clerk's or totalizer selecting keys 101 are each provided with a pin 102 co-operating with the cam edge 103 of a related cam plate 104 loosely mounted upon the rod 97 and having a finger 105 engaging the under side of the corresponding throw-out bail 98.

When one of the totalizer selecting keys 101 is depressed to its "coupler lifting position" the shaft 36 will be driven, as previously described, and the complementary cams 86 acting upon the lever 85 will rock the bail 87 clockwise and through the arm 88 and connections to the totalizer engaging slides 90 and 91 will tend to move both slides downwardly so that the cam slots 92 of the latter, co-operating with the totalizer supporting shafts 43, would serve to rock both totalizer frames about their pivotal points to bring the totalizer pinions into engagement with the actuating racks. However, the stud 102 of the selecting key 101 being depressed, acting upon the cam edge 103 of its related plate 104 will, at the same time, cause the finger 105 to move its associated throw-out bail 98 upwardly and, through the connected arm 99 and pin 100, will rock the associated throw-out cam plate 95 rearwardly. Thus, at the same time that the arm 88 was tending to move both of the totalizer engaging slides 90 and 91 downwardly a throw-out cam plate, associated with one of the slides, was being forced rearwardly. The configuration of the cam slots 95 of the throw-out plates 93, 94 is

such that when either plate is rocked about its pivotal point 89 it will, through the pin 96, tend to raise its associated totalizer controlling slide, but since, at this time, the lever 88 is tending to rock the pair of slides downwardly the result of these two tendencies is that one slide will remain substantially in its normal position while only the other is shifted, and, therefore, only one totalizer, corresponding to the shifted slide, will be brought into engagement with the actuating racks and the other will remain in its normal position. Upon a continued depression of the keys the item will be entered in the selected totalizer, after which the totalizer engaging mechanism will again be effective, in the reverse direction, to disengage the selected totalizer and permit the return of the actuators without affecting the amount inserted in this totalizer.

The totalizers which are actuated during item entering operations are alike in all respects and a description of one totalizer will suffice. Referring to Fig. 2 the totalizer is mounted in a frame 40 formed with ears 41 and 42 supporting a shaft 43. Each totalizer wheel 44, to which is attached its associated totalizer pinion 45 and transfer disc 46, is loosely mounted upon this shaft. Below and parallel to the shaft just mentioned is a second shaft 47. This shaft carries the various devices for effecting transfers which will be explained more in detail hereinafter. In alignment with the shaft 47 are two bearings 48 and 49 which are adapted to receive studs carried by the side frame which support the totalizer so that the totalizer frame may be oscillated bodily about the studs to move the totalizer pinions into or out of engagement with the actuating segments.

In the particular illustrative embodiment the totalizer comprises seven adding wheels 44 but this number may be altered to meet the requirements of a particular registering capacity. Each adding wheel 44 and attached parts are practically duplicates and a description of one will suffice for all.

As shown in Fig. 2, each adding wheel has secured thereto at its right a disk 46 carrying a trip tooth 50 (Figs. 3 and 4) and to the right of each disk is secured a totalizer pinion 45 carrying ten teeth. It will be evident that if, for example, the units adding wheel is moved during an item entering operation so that it passes from its nine to its zero position, a unit must be transferred from the units to the tens wheel in order that the adding wheels will indicate the true amount. In general, provision must be made to transmit a unit to any higher denominational order each time that the next lower denominational order adding wheel passes from its nine to its zero position. At times it is necessary to effect transfers by transfers, and to make the method clearer assume that 923

stands on the totalizer and 79 is to be added. At the end of the operation the totalizer wheels should, of course, indicate the total 1002. The units pinion during the operation 5 will be moved nine steps by its actuator through "0" to its "2" position and, of course, a unit should be carried to the tens wheel. The tens pinion, however, by the movement 10 of its actuator and the carrying mechanism will have passed from the "2" position to its "0" position and it will be necessary to carry a unit to the hundreds totalizer wheel, and in the same manner since the hundred totalizer wheel now stands at "0", a unit must be 15 transferred to the thousands totalizer wheel in order to represent the correct total. In the present embodiment, if "one" should be transferred to a wheel of the next higher order while the same wheel is simultaneously 20 being actuated by the actuators, a unit would be lost and incorrect total would result. For this reason it is necessary that some provision be made to prevent such loss of a unit which may be accomplished by having the 25 transfers effected upon the upstroke of the keys, that is, when the totalizer pinions are out of mesh with the actuators. Furthermore, in order to effect transfers by transfers it is necessary to actuate the transfer mechanism successively, first the transfer mechanism between the units and tens order, then the transfer mechanism between the tens and hundreds order, etc.

With the above in mind the method of effecting transfers between successive orders 30 will now be explained. The mechanisms for effecting transfers between successive denominational orders are alike, and in view of this fact the transfer mechanism between the 35 units and tens order only will be described.

As stated before, each totalizer wheel (Fig. 3) has attached to it at one side a transfer disk 46 which carries a trip tooth 50. Pivoted 40 upon the shaft 47 is a trip pawl 51 (Figs. 2, 3, 45 and 8) which is provided with a trip tooth 52 in the line of travel of the trip tooth 50 and adapted to engage therewith as the totalizer wheel 45 passes from its "9" to its "0" position. As shown more clearly in the perspective drawing of Fig. 8 the trip pawl 51 is furthermore provided with two notches 53 and 54 and a transverse lug 55. Adjacent to the trip pawl 51 is a slidably mounted transfer pawl 56 provided with a slot 57 engaging 50 the shaft 47 (Figs. 3 and 8). One side of the transfer pawl 56 is provided with a stud 58 which is in alignment with the notches 53 and 54 of the trip pawl 51 and so arranged that when the transfer pawl is in its rearward position (Fig. 3) the stud 58 will engage the notch 53 and when the transfer pawl is forced 60 forwardly to its transfer position, by means which will presently be described, the stud 58 will engage the notch 54. A spring 59 located in a suitable recess formed in the total-

izer frame bears against a tail 60 formed on the trip pawl 51 and insures that the stud 58 co-operates with either the notch 53 or the notch 54 when the transfer pawl is moved from one position to another. The transfer 70 pawl has integral with its upper end, or otherwise secured or attached by any desirable means, a plate 61 which carries a transfer tooth 62 (Fig. 8) which is in the plane of the totalizer pinion 45 of the next higher 75 denominational order, and will engage at times one of the teeth of the pinion to advance the totalizer pinion a unit when transfers are to be effected. The transfer pawl 56 is further provided at its forward end with a square shoulder 63 which normally (Fig. 3) contacts with the lug 55 of the trip pawl 51, and at its rear end it is provided with a slot or notch 64 in which operates a stud 65 carried by a transfer operating arm 66.

The transfer operating arms 66 are loosely mounted upon the shaft 31 and are provided with rearward extensions 67 (Figs. 1, 9 and 11) carrying oppositely projecting anti-friction rollers 68 and 69 thereof. Upon the rotation shaft 35, which, as stated before, is given a complete rotation upon each operation of the machine, is secured a series of complementary cams 70 and 71 the peripheries of which are in contact with their associated anti-friction rollers.

The sequence of operations of the transfer devices is illustrated in Fig. 3, 5, 6 and 7, Fig. 3, showing the normal position of the totalizer. When a Clerk's or Coupler lifting key 100 is depressed to its coupling position the shaft 35 will be partially rotated to rotate the cams 70 and 71 in the direction of the arrow shown in Fig. 9. The rollers 69 will drop from their peak 72 of the cams 71 to the substantially concentric portions 73 thus forcing their respective transfer arms 66 downwardly simultaneously so that their studs 65 will occupy the position shown in the upper dotted circle of Fig. 3. The totalizer 105 engaging mechanism has meanwhile, been brought into operation so that the totalizer pinions are thrown into engagement with the segmental racks. From Fig. 3 it will be apparent that the forward ends of the transfer pawls 56 abut against the totalizer frame 40 and if the rearward ends of the transfer pawls were held by the studs 65 the totalizer pinions could not be 110 thrown into mesh. For this reason the arms 66 are given a downward movement at the same time the totalizer pinions are thrown into mesh with their actuators, and when in this position the pinions may be rotated without any interference with their corresponding transfer teeth 62.

The totalizer pinions are shown in engagement with the segmental racks in Fig. 5. If, for example, "1" has been standing upon the 115 units totalizer wheel, and "9" is to be added 120

thereto, the segmental rack will advance the units pinion wheel nine steps and in so doing the totalizer wheel will pass from nine to zero. The trip tooth 50 of the units totalizer wheel 5 will now contact with the trip tooth 52 of the trip pawl and force the lug 55 against the shoulder 63 of the transfer pawl 56. The stud 58 attached to the transfer pawl will now be disengaged from the notch 53 and 10 upon a further rotation of the trip pawl 51 the lug 55 will force the transfer pawl 56 forward until the shaft 47 contacts with the opposite end of the slot 57, as clearly seen in Fig. 5. It will be noted from this and other 15 figures that the walls of slot 57, the upper wall of notch 64 and the sliding outer surface 561 of the pawl 56 are all in parallel relation to permit the sliding movement of the pawl just explained.

20 Upon a further movement of the disk 46 the trip tooth 50 will clear the trip tooth 52 of the trip pawl 51 and by virtue of the tension stored in the spring 59 during the previous operation the trip pawl 51 will snap 25 upwardly until the stud 58 of the transfer pawl 56 is engaged by the notch 54 of the trip pawl 51. It is of course evident that since the roller 69 has engaged the concentric portion of the cam 71 no rocking of the 30 transfer arm 66 will result during the depression of the keys. The transfer device is now in a position to advance the tens wheel a unit.

Referring to Figs. 11 to 14 it will be noted 35 that the cams 70 and 71 for the transfer pawls of the various denominational orders are not identical in contour. The foremost cam 70 shown in Fig. 12 and the cam 71 shown in Fig. 13 constitute the pair of cams for actuating the highest order transfer pawls, while the complementary cams shown in Fig. 14 constitute the cams for actuating the lowest denominational order pawls; the positions of the cams shown in Figs. 12 to 14 40 being those assumed when in normal position or the position assumed before the keys have been operated. It is apparent that the concentric portions 73 of all of the cams 71 are the same and consequently 45 all of the rollers 69 will engage said portions 73 simultaneously thereby causing all of the transfer arms 66 to move downwardly at the same time, thus causing the studs 65 on said arms 66 to assume the position 50 of the upper dotted circle shown in Fig. 3. Again, when the cams are rotated through substantially 180° the cam portions 731 on all of the cams 71 will simultaneously engage their respective rollers 69 and thereby 55 cause the arms 66 to move upwardly to the position shown in Fig. 3, thus permitting the totalizers to move out of engagement with their actuating racks. The totalizers are 60 now in condition to receive transfers. From 65 Figs. 12 to 14 it is seen that the cam por-

tions 74 on cams 70 and the corresponding notches 74' on cams 71 are arranged spirally about the shaft 35 so that transfers will be effected in the totalizers seriatim beginning with the lowest or tens order. Near the 70 end of the down stroke of the keys or, if desired, during the first part of the up stroke, the rollers 69 will engage the cam portions 731 of cams 71 and rock the arms 66 upwardly, as aforesaid. Now, as the roller 75 68 for the tens order engages the high portion 74 of its cam 70 the corresponding notch 74' on cam 71 will be opposite its roller 69, thus the transfer arm 66 for that order will be rocked downwardly to effect a transfer 80 to the next higher order. It is clear that the arms for the hundreds, thousands, etc., groups, will follow successively, due to the spiral arrangement of the cam portions 74 and notches 74' on cams 70 and 71, respectively. As the transfer arm 66 begins its downward movement the stud 65 engages the lower edge of the slot 64 and rocks the rear end of the transfer pawl downwardly and then slides it bodily till the forward end 571 of the 90 slot 57 engages the shaft 47 (Fig. 7), the trip tooth 62 having engaged one of the teeth of the totalizer pinions of the tens order to advance it a step. While the transfer pawl has been rocked the stud 58 carried thereby has, by virtue of the sliding movement imparted to the pawl while effecting the transfer, been disengaged from the notch 54 to occupy the notch 53. As the transfer arm 66 returns to its normal position the parts will again assume the position 95 illustrated in Fig. 3.

In the illustrative embodiment, as is clearly shown in Fig. 11, six transfer arms are provided, but it is evident that if the registering capacity of the totalizer be altered a 100 corresponding number of arms must be provided.

Fig. 4 illustrates the condition which exists when a transfer by a transfer is to be effected. To make this clearer assume that the tens wheel had been standing in its nine position and one has been added to it by the transfer operation just described. It is necessary, of course, that a unit be added 110 to the hundreds totalizer wheel. As a unit is being transferred to the tens totalizer wheel (Fig. 4) the totalizer pinion will advance from its nine to its zero position and in so doing will trip the pawl 51 associated 115 with the transfer mechanism between the tens and hundreds totalizer wheel and set the transfer pawl 56 to perform a carrying operation. During the return or up-stroke of the keys and after the transfer arm 66 associated 120 with the transfer device between the units and tens order has been actuated, the transfer arm 66 associated with the transfer device between the tens and hundreds order will be actuated and advance the 130

hundreds totalizer wheel one step in the manner previously set forth.

Machines of this character are at times subjected to improper usage by persons who desire them to work improperly, and in order to effect a mis-operation of the machine they have operated the machine rapidly and with a considerable degree of force and violence. In rapid operations the sequence of events occur almost instantly and if considerable force was utilized in operating the machine the transfer mechanism might impart such a rapid rotation to the totalizer wheels as to cause the totalizer to over-carry, with a result that an incorrect registration would be indicated. To preclude the possibility of over-carrying the following mechanism is employed.

The plate 61 heretofore mentioned is provided with a notch 75 located forward of the transfer-tooth 62, as is readily seen from Fig. 8. As the transfer pawl 56 is being rocked downwardly by its operating arm 66 the transfer tooth 62 will engage a tooth of the transfer pinion wheel to advance the same (Fig. 7). It will be readily understood that if the transfer arm 66 was actuated rapidly the transfer tooth 62 would impart such a rapid rotation to the totalizer wheel as to over-carry. The notch 75 is so positioned with relation to the totalizer pinion as to engage one of the teeth as the pinion is being advanced by the transfer tooth 62, as is clearly shown in Fig. 7, thus stopping the movement of the totalizer pinion and preventing the possibility of overthrow.

To prevent accidental displacement of the totalizer pinions from their set positions when disengaged from their actuators as well as to assist in preventing over rotation of the totalizer wheels due to momentum there is provided a series of pawls 80. (Figs. 2, 7, and 8). The pawls 80 are loosely pivoted upon the shaft 47 and urged rearwardly by springs 81 so that their wedge shaped ends 82 engage the interdental space of the corresponding totalizer pinion.

From the foregoing description it will be evident that during each operation of the machine the transfer pawls 56 are actuated by their associated transfer operating arms irrespective whether transfers are to be effected. When no transfers are to take place the rearward end of the transfer pawl will be rocked downwardly about the shaft 47 as a pivot and the tooth 62 will be carried rearwardly but will not engage the teeth of the pinion wheel.

Any suitable mechanism may be provided for resetting the totalizer pinions to zero, such as for example that shown in the Fuller application S. N. 263,125.

Although this type of transfer mechanism has been shown in connection with a particular type of cash register it is not the de-

sire to confine its application to this particular type of machine as it is readily evident that with minor changes it may be applied to other forms of cash registers, accounting machines and other devices where transfer mechanisms are necessary and employed.

While the form of mechanism herein shown and described is admirably adapted to fulfill the objects primarily stated it is to be understood that it is not intended to confine the invention to the one form of embodiment herein shown and described as it is susceptible of embodiment in various forms all coming within the scope of the claims which follow:

What I claim is:—

1. In a machine of the class described, the combination comprising movable elements and a transfer tripping projection movable with one of said elements, of a transfer trip pawl actuated by said projection, a transfer actuating pawl set by actuation of the trip pawl, a transfer operating arm, totalizer actuators, means for effecting a relative movement of the movable elements and actuators to effect engagement and disengagement of the elements and actuators, a stud on the transfer operating arm for transmitting movements of the arm to the transfer actuating pawl, said stud being normally held in a position preventing the relative engaging movement of the actuators and elements and means for giving the transfer arm a preliminary movement to carry the stud out of said preventing position.

2. In a machine of the class described, the combination of a totalizer comprising movable elements and a transfer tripping projection movable with one of said elements, of a transfer trip pawl actuated by said projection, a transfer actuating pawl set by actuation of the trip pawl, a transfer operating arm, totalizer actuators, means for effecting a relative movement of the totalizer and actuators to effect engagement and disengagement of the totalizer and actuators, a stud on the transfer operating arm for transmitting movements of the arm to the transfer actuating pawl, said stud being normally held in a position preventing the relative engaging movement of the actuators and totalizer, means for giving the transfer arm a preliminary movement to carry the stud out of said preventing position, and for subsequently giving the transfer arm a further movement to actuate the transfer actuating pawl.

3. In a machine of the class described, a main operating shaft, a pivotally mounted totalizer frame, a totalizer carried by said frame comprising wheels of successive denominational order, pivoted actuators for operating said totalizer, transfer elements carried by said totalizer frame and adapted to co-operate with said totalizer wheels, and means co-operating with said main operat-

ing shaft for rocking said totalizer frame to engage the totalizer with said actuators and simultaneously and independently rocking said transfer elements to permit the rocking 5 of said frame.

4. The combination of a totalizer wheel comprising a pinion, a transfer pawl adapted for rotary and longitudinal movement relative to a fixed shaft passing through said 10 pawl, and invariably operated means directly acting upon said pawl for first rotating said pawl to engage its tooth with said pinion and then sliding said pawl to rotate said pinion.

5. In a machine of the class described having 15 a totalizer comprising a series of denominational orders including a pinion, a transfer pawl adapted to co-operate with a pinion, said pawl being adapted for rotary and longitudinal movement when a transfer is to 20 be effected and only rotary movement when no transfer is to be effected.

6. In a machine of the class described, a main operating shaft, a totalizer comprising a plurality of numeral wheels arranged 25 in denominational order, a transfer pawl adapted to be given a rotary and longitudinal movement, means carried by a wheel of lower order for imparting a longitudinal movement to said pawl, and means operated by the main 30 shaft of the machine for giving said pawl a rotary and then a longitudinal movement.

7. In a totalizer including wheels of several denominational orders, a transfer pawl for carrying a unit from a wheel of lower order to the wheel of next higher order comprising a tooth for engaging the wheel of higher order, said pawl having a supporting slot therein permitting rotary and longitudinal movement of said pawl and a notch in 40 one end partially enclosed by a hook which is adapted to be engaged to give to said pawl both a rotary and longitudinal movement.

8. A transfer pawl adapted for rotary and sliding movement comprising an exterior 45 sliding surface, an elongated supporting slot, and an engaging notch, said surface, slot and notch each having a side parallel to the direction of sliding movement of said pawl.

9. In a machine of the class described, a main operating shaft, a transfer pawl, a cam 50 on said shaft, and means connecting said cam with said pawl whereby the cam will give to said pawl a preliminary rocking movement, a return movement and then a combined 55 rocking and sliding movement for the purpose described, and means associated with said pawl for conditioning the same for the sliding movement imparted thereto by said cam.

60 10. In a machine of the class described, a main operating mechanism, a plurality of totalizers each comprising a series of wheels, a plurality of transfer pawls each of which is provided with an elongated slot and an en- 65 gaging notch, a shaft embraced by said slot

thereby adapting said pawls for rotary and sliding movement, there being one of said pawls for an order of each totalizer and a pivoted arm common to the totalizers carrying means cooperating with said notches for imparting both rotary and sliding movement to said pawls. 70

11. In a machine of the class described a totalizer comprising a plurality of registering elements of successive orders, transfer 75 pawls for operating said elements each under the control of the next lower order element, operating arms for actuating said pawls upon each operation of the machine, and a main operating means with connections for rocking said arms simultaneously a slight amount and subsequently rocking said arms singly and successively during one operation of the machine. 80

12. In a machine of the class described a 85 totalizer comprising a plurality of registering elements of successive orders, transfer pawls for operating said elements each under the control of the next lower order element, operating arms for actuating said pawls 90 upon each operation of the machine, and a main operating means with connections for rocking said arms simultaneously a slight amount to permit rocking of said totalizer, and subsequently rocking said arms singly 95 and successively for effecting transfers into higher orders during one operation of the machine.

13. In a machine of the class described a 100 totalizer comprising a plurality of registering elements of successive orders, actuators for said elements, transfer pawls operatively associated with said elements, operating arms for said transfer pawls, a main drive shaft, connections from said shaft for moving said 105 totalizer into engagement with the actuators, and means operated by said shaft for simultaneously rocking all of said arms when the totalizer is being moved and at another time for rocking said arms successively for effecting transfers. 110

14. In a machine of the class described, a totalizer pinion and a transfer pawl adapted to impart a single step of movement thereto comprising an operating tooth, supporting means permitting rotary and sliding movement, a hook whereby said pawl may be given a rotary and sliding movement to rotate said pinion and a locking notch adjacent said operating tooth adapted to positively arrest the movement of said pinion after the latter has moved one step. 115 120

15. In a machine of the class described, an operating mechanism, a totalizer comprising a series of denominational wheels, a normally inactive transfer pawl for one of said wheels, means for rendering said pawl active, and connections from said operating mechanism to give to said transfer pawl a rotary movement or a combined rotary and longitudinal 125 130

movement according to whether the pawl is inactive or active.

16. In a machine of the class described, a main operating shaft, a movable totalizer frame, a totalizer carried by said frame, actuators for operating said totalizer, transferring means cooperating with said totalizer and normally in a position preventing engagement of said totalizer with said actuators, and means cooperating with said main operating shaft for shifting said totalizer frame to engage the totalizer with said actuators and simultaneously removing said transferring means from said engagement preventing position.
17. In a machine of the class described, a totalizer including wheels of several denominational orders, a transfer pawl for carrying from a wheel of lower order to the wheel of next higher order comprising a tooth for engaging the wheel of higher order, said pawl having a supporting slot therein permitting rotary and longitudinal movement of said pawl and a notch in one end partially enclosed by a hook, and a member movable upon each operation of the machine and engageable with said hook for operating said pawl.

In witness whereof I have signed my name
20 hereto this 18th day of Dec., 1922.

CHARLES W. GREEN.
